UNITED STATES PATENT OFFICE.

CHESTER C. ZUGSCHWERDT, OF GARDEN CITY, SOUTH DAKOTA.

SHOCK-TYING DEVICE.

1,086,974.

Specification of Letters Patent. Patented Feb. 10, 1914.

Application filed July 9, 1913. Serial No. 778,189.

To all whom it may concern:

Be it known that I, CHESTER C. ZUGSCHWERDT, a citizen of the United States, residing at Garden City, in the county of Clark, State of South Dakota, have invented certain new and useful Improvements in Shock-Tying Devices; and I do hereby declare the following to be a full, clear, and exact description of the invention, such as will enable others skilled in the art to which it appertains to make and use the same.

This invention relates to shock tying devices.

The object of the invention resides in the provision of a shock tying device which will be simple, durable and efficient and by means of which corn shocks may be quickly and securely tied.

A further object of the invention resides in the provision of a device of the character described which may be conveniently applied to a shock in position for operation and removed after the shock has been tied for use in connection with another shock.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a side elevation showing the device applied to a shock; Fig. 2, a section on the line 2—2 of Fig. 1; Fig. 3, a rear view of the device detached; Fig. 4, a front view of same; Fig. 5, a section on the line 5—5 of Fig. 3, and Fig. 6, a section on the line 6—6 of Fig. 3.

Referring to the drawings the device is shown as comprising a shock embracing member which includes an intermediate section 10 and terminal sections 11 and 12, the terminal sections being hingedly connected to respective ends of the intermediate section. Secured to the rear side of the intermediate section 10 at each end of the latter are angle plates 13 which include a rearwardly directed arm 14. Secured to the rear side of the section 11 are angle plates 15 which include respectively rearwardly

directed arms 16, the latter being disposed adjacent to respective arms 14. Slidably

engaged through openings in adjacent arms 14 and 16 respectively are bolts 17. Encircling each bolt 17 is a spiral spring 18 one end of which bears against the adjacent arm 16 while the other end bears against the head of the bolt 17. These springs 18 constantly tend to hold the section 11 in alignment with the intermediate section 10 as will be obvious. Mounted on the rear side of the section 12 are angle plates 19 which include rearwardly extending arms 20 disposed adjacent respective arm 14 at one end of the intermediate section 10. Slidably engaged through openings in the arms 14 and 20 respectively are bolts 21 and encircling these bolts are spiral springs 22 one end of which bears against the arm 20 and the other end against the head of the bolt 21. These springs 22 tend to hold the section 12 in alignment with the intermediate section 10 as will be obvious. Secured to the sections 10, 11 and 12 respectively and projecting rearwardly therefrom are guide members 23. Mounted on the rear side of the section 10 is a bracket 24 in which is journaled a pulley 25. Also mounted upon the rear side of the section 10 is a bracket 26 which supports a receptacle 27 for the tying twine. The top of the receptacle 27 is provided with an opening 28 through which the twine is guided during the tying of the shock. Mounted upon the bracket 26 transversely of the latter is a knife 29 which serves as a means for conveniently severing the twine after each tying operation. Secured to the front side of the section 10 are forwardly directed rods 30 adapted to be inserted in the shock to support the device during its application and during the tying operation. Secured to the rear side of the section 12 is a resilient finger 31 the upper end of which is disposed in slightly spaced relation to the rear side of said section for a purpose that will presently appear. The device further includes a cable 32 which has a ring 33 secured to one end and a hand hold 34 secured to the other end, said cable being trained over the pulley 25.

In the use of the device the rods 30 are inserted into the shock. The cable is then carried around the shock and the ring 33 engaged over the guide member 23 carried by the intermediate section 10, said cable in this position passing through the guide members 23 carried by the sections 11 and

12. The hand hold 34 is then gripped and pulled upon with considerable force so as to bind the cable around the shock. This operation will cause the sections 11 and 12 5 to swing into embracing relation to the shock. When the shock has been bound by the cable 32 with the requisite tightness said cable is engaged between the finger 31 and the section 12 so as to lock same against 10 movement under the influence of the springs 18 and 22 and also under the influence of the expansive force of the temporarily bound shock. The shock is then tied by means of the twine contained in the receptacle 27 and 15 after the tying operation is complete the twine is severed by means of the knife 29. The cable 32 is then released by withdrawing same from between the finger 31 and the section 12. The ring 33 is then disengaged 20 from the guide member 23 and the parts of the device will then assume their normal position to permit ready disengagement of same from the shock.

What I claim is:—

25 1. In a shock tying device, an embracing member comprising intermediate and terminal sections, the latter being hingedly connected to respective ends of the former for movement into embracing relation to a 30 shock, spring means constantly tending to hold the terminal sections in alinement with the intermediate section, guide members ex-

tending rearwardly from said sections respectively, a bracket mounted on the rear side of the intermediate section, a pulley 35 journaled in said bracket, a cable trained over said pulley, and means for anchoring one end of the cable when same is disposed around a shock and around the outer ends of the terminal sections whereby said cable 40 may be tightened around the shock and the terminal sections moved into embracing relation thereto by a pull exerted upon the other end of the cable, and means for locking the cable against movement when tightened around a shock. 45

2. In a shock tying device, an embracing member comprising a plurality of hingedly connected sections, means carried by one of said sections for supporting the member 50 against the side of a shock, a cable having one end secured to one of the sections, and means for securing the other end of the cable to another section of the member whereby the cable may be held in embracing relation to the shock during the operation of tying the latter. 55

In testimony whereof, I affix my signature, in the presence of two witnesses.

CHESTER C. ZUGSCHWERDT.
